UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,027, dated November 9, 1880.

Application filed September 1, 1880. Term of patent 3½ years.

To all whom it may concern:

Be it known that I, CHARLES MAGEE, of Brooklyn, in the county of Kings and State of New York, have invented a new and original 5 Design for Carpet, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group consisting of a circular figure, *a*, with a bunch of flowers and leaves extending over a portion of the circumference of the circle and within the same. This figure *a* overlaps a rectangular figure, *b*, at one of its corners, which last figure *b* is ornamented with a spray of flowers and with lines of trident-shaped figures. The figure *a* also overlaps a large portion of another rectangular figure, *d*, and this last figure *d* is connected with a semi-circular figure, *e*, by a broad band. These figures *a b d e* form the group A.

The figure B is of curvilinear outline, and contains a bunch of flowers, as shown. The figure C is rectangular, with serrated outside lines, and is ornamented within by a bunch of

flowers, and has a circular rosette overlapped by a rectangular figure at one of its corners. 30 The figures C and B are somewhat connected by flowers growing from B upon long stalks, and the figure B is partly overlapped by the figure *a*. The repetition of the group and figures above described forms the whole design 35 of the carpet.

I claim—

1. The design for carpets, consisting of the group A, composed of the figures *a b d e*, substantially as shown. 40
2. The design for carpets, consisting of the figure B, substantially as shown.
3. The design for carpets, consisting of the figure C, substantially as shown.
4. The design for carpets, consisting of the group A and figure B, substantially as shown. 45
5. The design for carpets, consisting of the figures B and C, substantially as shown.
6. The design for carpets, consisting of the figures B C and group A, containing figures *a b d e*, substantially as shown. 50

CHARLES MAGEE.
